UNITED STATES PATENT OFFICE

GEORGE H. WHEATLEY, OF OAK PARK, ILLINOIS

COVERING

Application filed July 20, 1931. Serial No. 551,854.

This invention relates to covering, and with regard to certain more specific features to carpeting formed from a felted fabric and rubber.

5 Among the several objects of the invention may be noted the provision of a covering comprising a tenaciously joined felted fabric and rubber base; the provision of a covering of the class described which will not fray when cut, or when worn in particular spots; the provision of a covering of the class described which 10 is shock absorbing and a relatively efficient heat insulator, and which has a certain resilient quality whereby it is adapted to lay snugly over limited unevenness of floors; the provision of a covering of the class described which is readily adapted for use on the floors of motor cars; the provision of a covering of the class described in which the felted material is treated with rubber and vulcanized, and which may be suitably reinforced and/or 15 formed to give the appearance of woven fabric; and the provision of the method of manufacturing covering of the class described 20 which gives a strong, relatively cheap and attractive covering. Other objects will be in part obvious and in part pointed out hereinafter.

The invention accordingly comprises the 30 elements and combination of elements, features of construction and synthesis, and arrangements of parts, which will be exemplified in the structures hereinafter described, and the scope of the application of which 35 will be indicated in the following claim.

In the accompanying drawing, in which are illustrated one or more of various possible embodiments of the invention,

40 Fig. 1 is a trimetric view of a fragment of the finished covering, in this instance carpeting, showing the application of a molding screen thereto;

45 Fig. 2 is an exploded sectional view illustrating the raw materials of the invention prior to treatment thereof;

Fig. 3 is a section view illustrating the product at the termination of an early stage of manufacture;

Fig. 4 is a sectional view similar to Fig. 3 illustrating the finished covering; and,

50 Fig. 5 is a sectional view similar to Fig. 4 illustrating an alternative embodiment of the finished covering.

Similar reference characters indicate corresponding parts throughout the several 55 views of the drawing.

In my copending application, Serial Number 527,435, filed April 3, 1931, for "floor covering", I disclose a carpeting formed of a woven fabric wearing surface and a shock-absorbing sponge rubber backing therefor. While the carpeting therein disclosed is possessed of great utility, the necessity for binding the edges thereof to prevent raveling or 60 fraying of the fabric renders it uneconomical for use in small pieces, as for automobile floors. The present invention overcomes this difficulty and presents a covering which requires no edge binding whatsoever.

65 Referring to Fig. 1 there is shown at numeral 1 a piece of covering, in this instance carpeting, made according to the present invention which is especially adapted for use on the floors of automobiles and the like.

Prior carpeting of the class used for the 70 floors of motor cars has been made from a woven fabric. When subjected to wear in certain limited regions, the carpet wore through in those regions, and became ragged and frayed and presented an unsightly appearance before the remainder of the carpet showed any appreciable wear. Furthermore,

75 such a carpet required a binding around the edges to prevent the cut fabric from ravelling or fraying. A still further disadvantage of the plain fabric carpeting is that it is neither waterproof, sound, nor vibration absorbing

80 85 90 nor heat insulating, and accordingly the degree of utility comfort which the deep carpet

that a well furnished home affords was not available.

I have overcome the difficulties associated with the aforementioned carpet and have provided a new and improved type of covering which is resilient, heat insulating and vibration absorbing and which has a top surface which will not unravel or become ragged, and which may be cut to any size desired without necessity of binding the edges of the cut portions.

Referring now more particularly to Fig. 1, there is shown at numeral 1 a section of covering which comprises a sponge rubber layer 3 to the top of which is tenaciously, permanently joined a treated felted fabric 5.

The felt 5 before treated may comprise wool, wool and cotton, jute or other fibrous material felted together to form a finished but untreated felted mat 13 (see Fig. 2). In this condition the mat 13 has a large number of fibers 15 extending therefrom and the number of relatively large interstices therein is large.

The fabric 13 is first soaked with a rubber solution which may comprise for example, a rubber cement, a solution of rubber latex, or a water "solution" or suspension of rubber. After the felted material 13 has been so treated as to be impregnated throughout with the rubber solution, it is allowed to dry thoroughly and the dried and matted felted fabric is shown on top of the raw rubber composition in Fig. 3. This drying allows the solvent of the solution to evaporate and leaves the rubber around the fiber and filling the interstices. This drying also causes further matting of the fibers which matting provides a heavily matted, tough and wear resisting surface. The felt in this condition is quite sticky.

The sponge preformed rubber base 3 is formed from a rubber composition 11 (Fig. 2) which usually comprises a thoroughly intermixed mass of latex and/or partially cured rubber or the like, and such chemicals as, under the influence of heat, react to produce an aerating gas. Upon heating and vulcanizing, the rubber composition, as shown at numeral 11, expands and assumes the finished shock-absorbing base or under-side material shown at numeral 3, Figs. 1 and 4.

The treated dried fabric 13 and rubber composition 11 are assembled as shown in Fig. 3 and the composite material is now subjected to a heating or vulcanizing operation, as described in detail in my United States patent application, Serial No. 527,435, filed April 3, 1931, or otherwise. During this heating or vulcanizing operation the chemical or chemicals in the composition 11 are caused to react or generate gases which aerate or inflate the composition layer 11, thereby producing the sponged or vulcanized rubber layer 3.

The rubber in the rubber treated mat 13 assumes the characteristics shown in Fig. 1,

numeral 5 if that it loses its stickiness which it had after being treated with the rubber solution and prior to the heat treating.

If it is desired to effect a design, such as is shown at numeral 7, on the top of the exposed surface of the felted material 5, one method is to provide a woven metal screen 9 over the top of the carpeting 5 during the heating or vulcanization, and the effect is to produce a permanent design such as is shown at numeral 7 which design gives a woven effect to the cover. This is accomplished because the rubber in the felt is also vulcanized at a temperature corresponding to an optimum plastic state of the rubber and holds its vulcanized form when cooled.

Plate molds or screens having any suitable design may likewise be used to impress the felted material 5 during the vulcanizing operation. The mold may also be provided with cutting edges, whereby the covering is brought to exact size, during the vulcanizing operation with maximum simplicity.

In instances where a covering having a relatively higher tensile strength is desired, a layer of canvas 17 or like non-stretching material may be vulcanized to the bottom of the rubber base 3 at the time of vulcanizing process. With this canvas 17 placed on the bottom of the covering the covering will substantially resist stretching in all directions.

The product of the present invention as illustrated at numeral 1 has many advantages, among which is the soft resilient and deep feeling which the carpet transmits to the feet of an occupant of the car in which the carpet is installed.

The rubber and felt, being heat insulating, provide a cooler surface in the summer and a warmer surface in the winter. Inasmuch as the carpet has no woven fabric if as under the clutch pedal of a car, the heel of the operator wears the material 5 through to the rubber, the material 5 around the hole will not fray or become ragged inasmuch as it is of a felted construction. Further for this reason no edge binding is necessary.

Further, the fact that the felt 5 is fastened to such a resilient base helps the wearing qualities of the felting inasmuch as the resiliency of the base tends to take a great deal of the shock and thus the felt 5 gives with the base. Because the base is rubber it is adapted to lie on the floor without slipping.

A further advantage of the invention is that the product which is thus obtained is relatively inexpensive to produce because this type of covering may be made in a continuous strip by the vulcanizing machine described in my aforementioned patent application.

In view of the above, it will be seen that the several objects of the invention are achieved and other advantageous results attained.

As many changes could be made in carry-

ing out the above constructions without departing from the scope of the invention, it is intended that all matter contained in the above description or shown in the accompanying drawing shall be interpreted as illustrative and not in a limiting sense.

5 I claim:

Covering consisting of an exposed layer of
10 felt impregnated throughout with rubber,
and a preformed backing layer of rubber, said
layers being vulcanized together.

In testimony, I have signed my name to
this specification this 16th day of July, 1931.

GEORGE H. WHEATLEY.
